BAFFLE PACKING FOR HEAT EXCHANGERS

Application filed September 4, 1930. Serial No. 479,659.

This invention relates to a packing for the baffles of heat exchangers. In heat exchangers the baffles which divert the fluid in circulation so that it will pursue a longer course should fit closely to the wall of the enclosing shell in order to avoid leaks which permit a short-cut in the movement of the fluid and reduce the efficiency of the exchanger.

It is therefore the object of this invention to provide a packing between the baffle and the wall of the shell which permits the baffle and the tubes associated therewith to be readily and conveniently introduced into the shell and removed therefrom and still insure a tight joint between the baffle and the shell when the apparatus is in use so as to obtain the maximum efficiency.

In the accompanying drawings:

Figure 1 is a vertical longitudinal section of a heat exchanger equipped with this invention.

Figure 2 is a horizontal section of the same taken on line 2—2 Fig. 3.

Figure 3 is a cross section taken on line 3—3 Fig. 1.

Figure 4 is a fragmentary cross section, on an enlarged scale, taken on line 4—4 Fig. 5, and showing the packing between a longitudinal edge of the baffle and the adjacent part of the shell.

Figure 5 is a horizontal section taken on line 5—5 Fig. 4.

Figures 6 and 7 are fragmentary longitudinal sections of the baffle and the packing strip thereon showing different ways of arranging the opposing ends of adjacent sections of the packing strip.

In the following description similar characters of reference indicate like parts in the several figures of the drawings.

The numeral 10 represents the shell, casting or housing of the heat exchanger which is preferably made of sheet metal and arranged horizontally and provided with an inlet 11 for one of the fluids to be circulated and an outlet 12 whereby this fluid may discharge from the shell, said inlet and outlet being preferably constructed in the form of tubular necks which are arranged diametrically opposite each other on the

upper and lower sides of the shell adjacent to the front end thereof.

At its front end the shell is provided with an annular attaching ring or collar 13 the face of which is provided with an annular recess or rabbet 14 which contains a gasket or packing 15. At the rear end of the shell the same is provided with an annular attaching ring or collar 16 which forms part of a stuffing box as will be hereinafter described and which contains an internal annular rabbet or enlarged bore 17.

Within the shell a plurality of sets of heat exchanger tubes is arranged lengthwise, two sets 18 and 19 being shown in the present instance, the upper set 18 being arranged above the center of the shell and the lower set 19 below this center.

The front ends of these tubes are secured to a front tube sheet 20 which bears with the rear side of its marginal part against the gasket 15. Arranged in front of the shell and the front tube sheet is a hollow manifold body 21 which is provided at its rear end with an annular rabbet or recess 22 containing a gasket or packing 23 bearing against the front side of the marginal part of the front tube sheet 20, the latter being clamped between the front attaching ring 13 and the rear end of the manifold body 21 by means of fastening bolts 24 connecting the adjacent parts of the attaching collar 13 and this manifold body, as shown in Figs. 1 and 2.

On its upper side the manifold body is provided with an inlet 25 for another of the fluids to be circulated and on its lower side with an outlet 26 for this fluid, said inlet and outlet preferably having the form of tubular necks. Extending horizontally across the central part of the front manifold body is a partition 27 which divides the interior of the front manifold body into an upper connecting chamber 28 which communicates with the front ends of the upper sets of tubes 18, and a lower connecting chamber 29 which communicates with the front ends of the lower set of tubes 19, said partition 27 having its rear edge fitted against the adjacent central part of the

front tube sheet 20 through the medium of a packing or gasket 39 so as to form a leak-tight joint therebetween.

- Arranged in front of the front manifold body 5 is a cover 31 which is provided with a central horizontal rib 32 engaging with the front edge of the partition 27 through the medium of a gasket or packing 33 and having its marginal part connected with the rear end of the manifold body by means of bolts 34 and also bearing against a gasket or packing 35 which is seated in an annular recess or rabbet 36 on the front end of the manifold body, as best shown in Fig. 1.
- 15 The rear ends of the several heat exchange tubes are secured to the rear tube sheet 37 which latter is provided at its edge with a forwardly projecting joint sleeve 38 which extends forwardly into the interior of the shell 10. Arranged in rear of the rear tube sheet is a manifold cover 39 forming a connecting chamber 40 which places the rear ends of the upper and lower sets of heat exchange tubes in communication with each other. Adjacent to its margin this rear cover is provided with a forwardly projecting annular flange 41 which projects into the rabbet or recess 17 of the rear attaching collar and bears against a packing 42 there-
- 20 in. The marginal parts of the rear cover 39 and the rear attaching ring 16 are connected with each other by means of bolts 43 so that upon tightening these bolts the packing 42 will be compressed and held tightly around the sleeve 38 so as to prevent leakage from the space within the shell to the rear ends of the heat exchange tubes while at the same time permitting the rear tube sheet 37 to move lengthwise of the shell in
- 25 response to expansion and contraction of the heat exchange tubes resulting from changes in temperature of the fluids which are circulated through the shell and the heating tubes.
- 45 Arranged lengthwise between the upper and lower sets of the heat tubes 18, 19 is a baffle 44 which preferably has the form of a flat plate made of metal and extending in a horizontal plane. This baffle is connected at its front end with the rear side of the front tube sheet 20 by means of a welded joint 48 or other suitable means while the rear end of this baffle terminates short of the rear tube sheet 39 so as to form a trans-
- 50 fer gap or passage 49 therebetween. The longitudinal edges of this baffle are arranged close to the inner longitudinal side of the wall of the shell so that the circulating fluid entering, say through the inlet 11, will be compelled to be passed horizontally rearward through the upper passage 50 formed between the baffle 44 and the upper part of the shell, thence downwardly through the passage 49, thence horizontally forward
- 55 through the lower passage 51 formed be-

tween the baffle 44 and the lower part of the shell and thence out through the lower outlet 12. The other fluid which is to be circulated may enter, for example, through the inlet 25, thence through the upper connecting chamber 28, thence rearwardly through the upper set of tubes 18, thence downwardly through the rear connecting chamber 40, thence forwardly through the lower set of tubes 19, thence downwardly through the lower connecting chamber 29 and out through the outlet 26.

In the use of this apparatus the relatively hot and cold liquids to be circulated may be passed respectively either through the interior of the tubes or through the shell along the exterior of the tubes and these fluids may either move through their respective passages in parallelism or the same may move in opposite directions through their respective passages, the particular manner of handling these fluids being governed by conditions where the apparatus is installed, also the character of the fluids between which the heat is to be interchanged. In all cases however, the temperature of the fluid on the exterior of the tubes and the temperature of the fluids on the interior of these tubes influence one another by an exchange of the heat, tending to raise the temperature of the cooler liquid and lowering the temperature of the hot liquid.

In order to obtain the maximum heat exchanging efficiency of this apparatus it is necessary to maintain a leak-tight joint between the longitudinal edges of the baffle 44 and the wall 10 of the shell so as to prevent the fluid entering the shell from passing through the joints between the longitudinal edges of the baffle 44 and the wall 10 and make a short-cut from the inlet to the outlet end of the shell instead of being compelled to travel to and fro through out the length of the shell and around the rear edge of the baffle which constitutes a very much longer course for the fluid and insures a greater transmission of the heat from one of the streams of fluid to the other.

To insure a practically tight joint between the longitudinal edges of the baffle and the wall of the shell for this purpose, packing means are provided which are preferably constructed as follows:

Between each longitudinal edge of the baffle and the adjacent part of the shell is arranged a packing strip which in its preferred form is made up of a plurality of longitudinal sections which have their opposing ends arranged adjacent to each other so that in effect they produce one continuous strip. Each of these sections is preferably constructed of sheet metal which is of U-shape form in cross section and provides a transverse bearing web 52 which engages with its outer side against the inner side of

the adjacent part of the shell wall 10, as best shown in Figs. 4 and 5, and two longitudinal legs or flanges 53 projecting inwardly from the opposite longitudinal edges of the web 52 and engaging with opposite flat sides of the adjacent longitudinal edge portion of the baffle 44, as shown in the same figures.

The several sections of each packing strip are yieldingly held in engagement with the shell wall by spring means which in its preferred construction consists of an undulated or serpentine shaped strip of spring metal 54 which is arranged between the inner side of the packing strip webs 52 and the adjacent longitudinal edge of the baffle 44, and bears with its alternating crests against the adjacent web of the packing strip and the longitudinal edge of the baffle, as best shown in Fig. 5. By this means the strip of spring metal 54 tends to constantly press the packing strip away from the baffle and into engagement with the shell wall and thereby maintain a practically tight joint between the opposing longitudinal surfaces of the same through which the respective circulating fluid cannot pass and take a short-cut in its flow, but instead is compelled to take a longer course as above described, and thereby insure the maximum heat exchanging effect of the apparatus.

In order to prevent the packing strips from becoming detached from the baffle when the latter is withdrawn from the shell together with the cluster or bundle of tubes 18 and 19, limiting means are provided which in their preferred form consist of stop pins or screws 55 which are secured to the baffle 44 and extend through transverse slots 56 in the flanges of the respective packing strip, the pins which pass through the opposite flanges or legs of the same strip being preferably staggered relatively to each other so that the pins or screws can be inserted in the baffle from opposite sides of the same without interference with each other.

The opposing ends of adjacent sections of the packing strip may either abut against each other as shown at 57 in Fig. 6 or the same may extend one over the other in the form of an overlapping or telescopic joint, as shown at 58 in Fig. 7, but in either case the opposing ends of adjacent packing strip sections are arranged in close engagement so as to form a practically fluid-tight joint between the same.

By making the packing strips in sections the same can be applied to the baffle more readily and the same are also more flexible inasmuch as the several sections of each strip are free to adapt themselves individually to the contour of the adjacent part of the shell wall in case any inaccuracies or irregularities occur in the same, and thereby provide a leaktight joint between the baffle and the

cylinder wall throughout the length of the opposing surfaces of these members.

When the cluster of tubes is removed from the shell together with the baffle tube sheets and packing strips, the lateral movement of the packing strips relative to the baffle is limited by the stopping effect of the stop pins 55 engaging with the inner ends of the slots 56 in the flanges of the packing strips. Preparatory to introducing the tubes, sheets, baffle and packing strips into the shell the packing strips are pressed inwardly toward the longitudinal edges of the baffle a sufficient extent to permit the packing strips to pass into the shell, and after these strips have been introduced into the shell the same are released so as to permit the springs 54 to press the packing strips outwardly into engagement with the shell wall and form a tight joint therewith.

This means for packing the joint between the baffle and the shell wall avoids the necessity of any accurate or expensive fitting of the baffle relative to the wall of the shell and instead permits of leaving a clearance space of varying width between the longitudinal edges of the baffle and the shell wall which permits of the free introduction of the baffle into the shell and the removal therefrom but still maintains a practically fluid-tight joint between the baffle and the shell wall when the apparatus is assembled for use.

Moreover, this construction of packing device between the baffle and shell is very simple and inexpensive in construction and not only capable of being easily applied to the baffle but is also not liable to get out of order.

I claim as my invention:

1. A heat exchanger comprising a shell having a fluid inlet and a fluid outlet, a plurality of sets of tubes arranged in said shell, tube sheets mounted at opposite ends of said shell and connected with opposite ends of said tubes, a baffle arranged between the sets of tubes and having longitudinal edges arranged adjacent to said shell, and packing means interposed between the longitudinal edges of said baffle and said shell and comprising a packing strip having a web engaging said shell and flanges on opposite longitudinal edges of said web which engage opposite sides of the longitudinal edge portion of said baffle, and spring means for holding said packing strip yieldingly in engagement with said shell.

2. A heat exchanger comprising a shell having a fluid inlet and a fluid outlet, a plurality of sets of tubes arranged in said shell, tube sheets mounted at opposite ends of said shell and connected with opposite ends of said tubes, a baffle arranged between the sets of tubes and having longitudinal edges arranged adjacent to said shell, and

- packing means interposed between the longitudinal edges of said baffle and said shell and comprising a packing strip having a web engaging said shell and flanges on opposite longitudinal edges of said web which engage opposite sides of the longitudinal edge portion of said baffle, and a serpentine spring interposed between the edge of said baffle and the inner side of said web and operating to hold the packing strip yieldingly in engagement with said shell.
3. A heat exchanger comprising a shell having a fluid inlet and a fluid outlet, a plurality of sets of tubes arranged in said shell, tube sheets mounted at opposite ends of said shell and connected with opposite ends of said tubes, a baffle arranged between the sets of tubes and having longitudinal edges arranged adjacent to said shell, and packing means interposed between the longitudinal edges of said baffle and said shell and comprising a packing strip having a web engaging said shell and flanges on opposite longitudinal edges of said web which engage opposite sides of the longitudinal edge portion of said baffle, said strip being made in sections and the ends of adjacent sections overlapping one over the other.
4. A heat exchanger comprising a shell having a fluid inlet and a fluid outlet, a plurality of sets of tubes arranged in said shell, tube sheets mounted at opposite ends of said shell and connected with opposite ends of said tubes, a baffle arranged between the sets of tubes and having longitudinal edges arranged adjacent to said shell, and packing means interposed between the longitudinal edges of said baffle and said shell and comprising a packing strip having a web engaging said shell and flanges on opposite longitudinal edges of said web which engage opposite sides of the longitudinal edge portion of said baffle and are provided with transverse guide slots, retaining pins secured to said baffle and passing through said slots, and spring means for holding said packing strip yieldingly in engagement with said shell.
5. A heat exchanger comprising a shell having a fluid inlet and a fluid outlet, a plurality of sets of tubes arranged in said shell, tube sheets mounted at opposite ends of said shell and connected with opposite ends of said tubes, a baffle arranged between the sets of tubes and having longitudinal edges arranged adjacent to said shell, and packing means interposed between the longitudinal edges of said baffle and said shell and comprising a packing strip having a web engaging said shell and flanges on opposite longitudinal edges of said web which engage opposite sides of the longitudinal edge portion, said strip being made in sections and the end of adjacent sections being close together.
6. A heat exchanger comprising a shell having a fluid inlet and a fluid outlet, a plurality of sets of tubes arranged in said shell, tube sheets mounted at opposite ends of said shell and connected with opposite ends of said tubes, a baffle arranged between the sets of tubes and having longitudinal edges arranged adjacent to said shell, and packing means interposed between the longitudinal edges of said baffle and said shell and comprising a packing strip having a web engaging said shell and flanges on opposite longitudinal edges of said web which engage opposite sides of the longitudinal edge portion of said baffle, said strip being made in sections and the ends of adjacent sections overlapping one over the other.
- In testimony whereof I hereby affix my signature.
